Attorneys

UNITED STATES PATENT OFFICE.

FRANK W. FOLEY, OF DOLLAR BAY, MICHIGAN.

HAMMER.

1,424,161.

Specification of Letters Patent.

Patented Aug. 1, 1922.

Application filed April 6, 1922. Serial No. 550,121.

To all whom it may concern:

Be it known that I, FRANK W. FOLEY, a citizen of the United States, residing at 55
Dollar Bay, in the county of Houghton and
5 State of Michigan, have invented certain
new and useful Improvements in Hammers,
of which the following is a specification.

This invention relates to hammers, and
has as an object the provision of a hammer
10 having faces of different degrees of hardness
so constructed that the union of the
materials of which the hammer head is made
will not be broken in service.

A further object of the invention is the
15 provision of a hammer of this character
which will be simple to manufacture.

An illustrative embodiment of the invention
is shown in the accompanying drawing,
in which

20 Fig. 1 is a perspective view;

Fig. 2 is a section on line 2—2 of Fig. 1
on a reduced scale;

25 Fig. 3 is a vertical longitudinal section
showing a step in the manufacture of the
hammer, and

Fig. 4 is a like section of the completed
hammer.

The hammer is shown as formed of a soft
metal carrying the eye 10 for the handle 11,
30 and one face 12 of the hammer formed
integral with the portion bearing the eye. The
portion of the hammer already described be-
ing the body of the hammer head is prefer-
ably formed of a soft metal such as copper.

35 To provide a hard face upon the hammer
a shell 13 of a hard material, as steel, is se-
cured to the head of soft material. To se-
cure the shell upon the head so as to remove
any tendency of separation the shell is made
40 with a recess 14 which is circular in cross
section, as indicated in Fig. 2, and which is
of larger diameter at its bottom portion 15
than at its opening 16.

The soft head of the hammer as first
45 formed has a projection 17 which is cylind-
rical in cross section and of uniform di-
ameter from the shoulder 18 to the extremity.
The diameter of the projection 17 as origi-
nally formed is substantially equal to the
50 diameter of the opening 16 into the recess in
the shell 13. With the parts formed as de-
scribed the projection 17 is inserted into the

hollow shell, as indicated in Fig. 3, and pres-
sure is applied to the parts sufficient to force
the soft head into the shell and to cause the 55
soft metal to completely fill the hollow in
the shell and to bring the shoulder 18 into
contact with the end 19 of the shell, thereby
providing a tight joint upon the surface.

When the hard face of the hammer is 60
used the impact of the blows thereon will
only tend to secure the soft metal therein
the more tightly. This is also true of blows
delivered with the soft face of the hammer,
since the whole effect of the momentum of 65
the hard shell when the soft face of the
hammer is used will be to drive the shell
more firmly upon the projection 17.

The tool will be found very convenient in
machine work where it is desired to strike 70
some parts without marring them, in which
case the soft face is used and where it is at
other times desired to up-set rivets, in which
case the hard face may be used.

In addition to the advantage of having the 75
soft and hard faces, the hammer will be
heavier when the head is made up largely of
the soft material, such as copper, than would
be the case if the main portion of the head
were made up of steel with a copper face 80
attached.

Minor changes may be made in the physi-
cal embodiment of the invention without de-
parting from its spirit.

I claim:

1. A hammer comprising a head of rela-
tively soft material carrying a hammer face
and an eye for a handle and a hard face
secured to said head enclosing one end there-
of.

2. A hammer comprising, in combination,
a head of relatively soft material having a
face of the said material and an eye for a
handle, a shell of relatively hard material
having a hollow therein, which hollow has 90
a mouth of reduced diameter, a projecting
portion of said head extending into said hol-
low and pressed therein to expand to com-
pletely fill the hollow whereby the shell will
be immovably secured to the head and 100
whereby relatively soft and hard faces are
provided for use.

FRANK W. FOLEY.
